(57) **CLAIM**

The ornamental design for an electric contact, as shown and described.

DESCRIPTION

FIG. 1 is a top, front and left side perspective view of an electric contact;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged view of the section thereof as indicated in FIG. 1;

FIG. 9 is an enlarged view of the section thereof as indicated in FIG. 2;

FIG. 10 is an enlarged view of the section thereof as indicated in FIG. 3;

FIG. 11 is an enlarged left side elevational view thereof;

FIG. 12 is an enlarged right side elevational view thereof;

FIG. 13 is an enlarged view of the section thereof as indicated in FIG. 6;

FIG. 14 is an enlarged view of the section thereof as indicated in FIG. 7;

FIG. 15 is an enlarged view of the section thereof as indicated in FIG. 9; and,

FIG. 16 is a cross-sectional view thereof, taken along section line 16-16 of FIG. 15.

The broken lines shown in the drawings illustrate portions of the electric contact that form no part of the claimed design. The long dash-short dash lines represent the boundary between claimed and unclaimed design and form no part of the claimed design.
